CHARGE FORMING DEVICE

Application filed May 31, 1930. Serial No. 457,694.

This invention relates to charge forming devices for internal combustion engines, and more particularly to devices of this character which comprise a plurality of primary carburetors, each of which delivers a primary mixture of fuel and air to one of a plurality of secondary mixing chambers located adjacent the engine intake ports and in which the primary mixture is mixed with additional air under certain operating conditions.

Devices of this character are disclosed in the copending applications of Fred E. Aseltine and Wilford H. Teeter, Serial No. 221,371, filed September 22, 1927, and Wilford H. Teeter, Serial No. 221,372, filed September 22, 1927.

It is an object of the present invention to provide novel means for operating the throttles and to secure better regulation of the mixture proportions.

According to this invention, instead of operating the secondary throttle by a lost motion connection from the primary throttle, the secondary throttle is operated directly by the operator through manually operating means and the primary throttle is connected to a suction operated valve in the secondary air passage, whereby said primary throttle is operated only through the medium of said automatic suction operated valve, and its movement is dependent on the suction effective on said valve and the flow of air through the secondary air passage.

Further objects and advantages of the present invention will be apparent from the following description, reference being had to the accompanying drawing wherein a preferred embodiment of one form of the present invention is clearly shown.

In the drawing:

Fig. 1 is a vertical, longitudinal section through a charge forming device considered in accordance with the present invention.

Fig. 2 is a fragmentary elevation of such device showing the operating connections for the throttle valve.

Fig. 3 is a section on the line 3—3 of Fig. 1.

The device disclosed comprises a main air manifold 10, having three outlet branches, the middle branch 12 being shown herein.

Each outlet branch communicates with one of the ports of a multicylinder engine and is provided with an attaching flange 14 for securing the manifold to the engine block in the usual manner, while a flange 16 is provided at the inlet for securing a carburetor unit thereto. The carburetor unit comprises the main housing 20 having an attaching flange 22 adapted to be secured to the flange 16 by screws 24. An air inlet coupling 26 is secured in an opening in the upper wall of the housing to admit air thereto. A casting 28, supporting devices disclosed later, is secured to the bottom of the main housing 20 and a sheet metal fuel bowl 30 is held tight against an annular shoulder 32 formed on said casting 28. Fuel is supplied to the fuel bowl from a main source of supply and its flow is controlled by a float 34, operating in the usual manner to maintain a substantially constant level of fuel in the bowl.

Fuel flows from the bowl to a plurality of fuel nozzles 36, one of which is located in each of the primary mixing chambers 38, more fully described later. The nozzles are supplied with fuel through a delivery conduit, comprising a vertical passage 40 having a fixed fuel inlet 42 and a high speed fuel inlet 44 controlled by a valve 46 operated as described in the first of the above mentioned applications. The passage 40 connects at its upper end with a horizontal fuel canal 48, which supplies fuel directly to each of the fuel nozzles 36 through orifices 50. A two-stage fuel metering valve 52 regulates the flow of fuel through the fuel delivery conduits and a check valve 54 received in a chamber 56, prevents the return of fuel on reduction of suction in the mixing chambers, all of the above described structure being identical with that more fully disclosed in application Serial No. 221,371.

Each primary fuel nozzle is provided with a main fuel outlet 58 in the top thereof and a secondary fuel outlet comprising two orifices 60 and 62 in the wall of the nozzle near the bottom of the mixing chamber. The secondary fuel outlets function at all times, while the suction in the primary mixing chamber is sufficient to lift fuel from the

- main outlet only at relatively high speeds. The primary mixing chambers comprise the enlarged anterior ends of primary mixture passages 64, which are parallel to each other and close together, as indicated in Fig. 3. When the carburetor is attached to the engine, these passages register with conduits which convey the primary mixture to secondary mixing chambers, as fully disclosed in the above application. One of these conduits comprises the tube 66 fixed in the wall of branch 12 of the manifold which supplies primary mixture to the secondary mixing chamber in that particular manifold branch. 15 A single throttle valve 68 which extends across all of the primary mixture passages, is provided with grooves 70, which register with said passages and control the flow therethrough. This throttle is journaled for rotation in the main housing and is operated by the means and in the manner hereinafter more fully described.

Air is admitted to the carburetor through the coupling 26 and is controlled by an air valve 72 held tight against a seat 74 by a spring 76, received between the valve and a flange 78, secured to a sleeve 80, slideable on a sleeve 82, fixed in the housing and guiding the movements of the stem 84 to which the air valve is secured. The air valve is adapted to be held closed to aid in starting the engine by lifting the flange 78 into engagement with the air valve through the medium of means which is not disclosed herein but is described in application Serial No. 221,371. Air to carry the starting fuel to the engine cylinders when the air valve is closed is supplied by the orifices 86.

The valve 72 admits air to a main air chamber 88, from which the air flows to the primary mixing chambers through an orifice 90 in the bottom of the chamber 88 and to secondary mixing chambers in the manifold through a secondary air passage 92, which 40 communicates with the manifold inlet. The flow of air through the passage 92 is controlled by a manually operable main throttle valve 94 and a suction operated valve 96, secured to shafts 98 and 100 respectively, which 45 are journaled for rotation in the main housing, the shaft 100 being off center with respect to the valve 96.

According to the present invention, the primary throttle valve 68 is not operated directly by a connection extending to the operator in the manner disclosed in the earlier applications above referred to. On the contrary, the main throttle valve 94 in the secondary air passage is operated in this manner and to this end an operating arm 102 is secured in any desirable manner to the end of the shaft 98 and such arm is pivotally connected to a rod 104, which is provided with an off-set end 106, extending through the end 60 of the arm 102, as indicated in Fig. 2. In

order to operate the primary throttle, the latter is provided with a spindle 108 projecting therefrom, to which is secured in any desirable manner, an operating arm 110, pivotally connected to the off-set end 112 of an operating link 114, the opposite end of which, 116, is bent and projects through an orifice in an arm 118, secured in any desirable manner to the end of the shaft 100, on which the suction operated valve 96 is secured. This valve is provided at its upper edge with an arcuate lip 120, which may be a separate piece secured to the valve or formed integral therewith, and projects from the valve, while the lower half of the valve is thickened so as to constitute a weight 122, which tends to close the valve from any open position. It will be clear that whenever the valve 94 is opened, the action of the air against the valve 96, the shaft of which is off center, also opens said valve 96. The projecting lip is provided to prevent any marked decrease in the force tending to open the valve as the latter moves toward open position. Due to the lip 120 the effective area of the upper part of the valve 96 as presented to the incoming air flowing through the secondary air passage, decreases very little as the valve is opened. Also during the opening of the valve the closing effect of the weight 122 is slightly decreased due to the fact that part of the weight moves to a position to the right of the shaft 100 and becomes effective to aid in opening the valves. By properly designing the lip and weight the effective force required to open the valve may be made substantially constant throughout the entire opening movement of the valve. Or if desired the lip and weight may be so proportioned that the force required to open the valve will increase as the velocity of the air flow through the secondary air passage increases, or any other desired result may be obtained.

As the suction operated valve 96 is moved toward open position the primary throttle is also opened through the medium of the operating linkage above described. It will be obvious that by suitably proportioning the lip 120 and weight 122 any desired movement of the primary throttle with respect to the manually operable secondary air throttle 94 may be obtained, either a movement equal to that of the valve 94, or a lesser movement.

To prevent fluttering of the main air valve and to retard its opening movement, a dash-pot is provided comprising a cylinder 124 which as shown is slideable in sleeve 126 integral with the casting 28, and a piston 128 secured to the lower end of the valve stem 84 and slideable within the cylinder 124. This particular dash-pot is provided for the purpose of enriching the mixture for acceleration, the cylinder being lifted as the throttle is opened, specific details of construction of

the dash-pot constitute no part of the present invention whatever and it is not necessary to employ the particular dash-pot shown, but as illustrated the cylinder may be lifted by an arm 130 as described in the earlier applications, but the dash-pot may be of any conventional construction.

It will be obvious that by the provision of the throttle operating mechanism disclosed herein the primary throttle is operated entirely automatically in accordance with the flow of air through the secondary air passage, and the position of the primary throttle may vary with changes in the velocity of flow through said secondary air passage, while the secondary air throttle valve remains in fixed position.

It should also be clear that by properly proportioning the lip 120 and weight 122 the mixture proportions may be regulated and certain difficulties such as enrichment of the mixture on opening of the throttle because of too much increase in the velocity head at the fuel nozzles, may be largely eliminated. For instance, if it be found, that when the primary throttle and secondary air throttle are moved through the same degree, the mixture becomes too rich. The device may be so constructed, that the primary throttle will not be opened as rapidly as valve 94, thus reducing the velocity head at the nozzles, with corresponding reduction in suction and flow of fuel from such nozzles.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a primary mixture passage, means for supplying fuel and air thereto, a secondary mixing chamber into which said mixture passage delivers a primary mixture of fuel and air, a secondary air passage supplying air thereto, and means controlled by the flow of air through the secondary air passage for increasing the quantity of primary mixture flowing through the primary mixture passage as the flow of secondary air increases.

2. A charge forming device for internal combustion engines comprising a primary mixture passage, means for supplying fuel and air thereto, a secondary mixing chamber into which said mixture passage delivers a primary mixture of fuel and air, a secondary air passage supplying air thereto, an air throttle therein, a primary throttle in said primary mixture passage and means controlled by the flow of air through said secondary air passage for controlling the position of the primary throttle in accordance with the position of the air throttle.

3. A charge forming device for internal

combustion engines comprising a primary mixture passage, means for supplying fuel and air thereto, a secondary mixing chamber into which said mixture passage delivers a primary mixture of fuel and air, a secondary air passage supplying air thereto, a primary throttle in said primary mixture passage and means for operating said primary throttle by the flow of air through said secondary air passage to open said throttle as the flow through the secondary air passage increases.

4. A charge forming device for internal combustion engines comprising a primary mixture passage, means for supplying fuel and air thereto, a secondary mixing chamber into which said mixture passage delivers, a primary throttle for controlling the flow through the primary mixture passage and a pressure responsive device for operating said throttle, said device being constructed to open the throttle as the engine speed increases.

5. A charge forming device for internal combustion engines comprising a primary mixture passage, means for supplying fuel and air thereto, a secondary mixing chamber into which said mixture passage delivers, an automatically operated primary throttle for controlling the flow through the primary mixture passage and constructed to open as the engine speed increases and manually operated means for controlling the operation of said throttle.

6. A charge forming device for internal combustion engines comprising a primary mixture passage, means for supplying fuel and air thereto, a secondary mixing chamber into which said mixture passage delivers, a primary throttle for controlling the flow through the primary mixture passage, suction operated means for operating the primary throttle, and designed to open the throttle on increase of speed, and manually operable means for controlling the operation of said throttle.

7. A charge forming device for internal combustion engines comprising a primary mixture passage, means for supplying fuel and air thereto, a secondary mixing chamber into which said mixture passage delivers, a primary throttle for controlling the flow through the primary mixture passage, a secondary air passage supplying air to said secondary mixing chamber, means operated by the flow of air through said secondary air passage for operating said primary throttle in accordance with its own movement and manually operated means for controlling the operation of said last mentioned means.

8. A charge forming device for internal combustion engines comprising a primary mixture passage, means for supplying fuel and air thereto, a secondary mixing chamber into which said mixture passage delivers, a primary throttle for controlling the flow

- through the primary mixture passage, a secondary air passage supplying air to said secondary mixing chamber, means operated by the flow of air through said secondary air passage for operating said primary throttle in accordance with its own movement and manually operated means for controlling the flow of air through said secondary mixture passage.
- 10 9. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, an air throttle for controlling the flow of air through the secondary air passage, and means for operating the primary throttle the effectiveness of which is controlled by the air throttle.
- 15 10. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, an air throttle for controlling the flow of air through the secondary air passage, and means for operating the primary throttle, said operating means being ineffective when the air throttle is closed and adapted to be rendered effective when the air throttle is opened.
- 20 11. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, and a suction operated valve in said secondary air passage, for controlling the flow therethrough and operating the primary throttle in accordance with its own movement.
- 25 12. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, a suction operated valve in said secondary air passage for controlling the flow therethrough, operating connections

extending from said valve to the primary throttle, and a manually operable valve in said secondary air passage controlling the opening of said suction operated valve.

13. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, a manually operable valve in the secondary air passage, a suction operated valve in said secondary air passage adapted to open on opening movements of the manually operable valve, and means for determining the amount of movement of said suction operated valve for any given movement of the manually operable valve.

14. A charge forming device for internal combustion engines comprising a primary mixture passage, means for supplying fuel and air thereto, a secondary mixing chamber into which the primary mixture passage delivers a primary mixture of fuel and air, a primary throttle controlling the flow through the primary mixture passage, a secondary air passage supplying air to the secondary mixing chamber, a manually operable valve in the secondary air passage, a suction operated valve in said secondary air passage adapted to open on opening movements of the manually operable valve, means for determining the amount of movement of said suction operated valve for any given movement of the manually operable valve, and a primary throttle operated by said suction operated valve.

In testimony whereof I hereto affix my signature.
